UNITED STATES PATENT OFFICE.

ERNEST M. MAGEE, OF PROVIDENCE, RHODE ISLAND.

DESIGN FOR A TEXTILE FABRIC OR SIMILAR ARTICLE OF MANUFACTURE.

Application filed February 9, 1927. Serial No. 20,664. Term of patent 3½ years.

To all whom it may concern:

Be it known that I, ERNEST M. MAGEE, a subject of the King of Great Britain, residing at Providence, in the county of Providence and State of Rhode Island, have invented a new, original, and ornamental Design for a Textile Fabric or Similar Article of Manufacture, of which the following is a specification, reference being had to the accompanying drawing forming a part thereof.

The figure shown is a plan view of a textile fabric or similar article of manufacture showing my new design.

I claim:

The ornamental design for a textile fabric or similar article of manufacture, as shown.

In testimony whereof I affix my signature.

ERNEST M. MAGEE.
